UNITED STATES PATENT OFFICE.

PASQUALE DELLA MONICA, OF HARRISON, NEW YORK.

WINDOW CONSTRUCTION.

Application filed August 19, 1921. Serial No. 493,555.

To all whom it may concern:

Be it known that I, PASQUALE DELLA MONICA, a citizen of the United States, residing at Harrison, in the county of Westchester and State of New York, have invented certain new and useful Improvements in Window Construction, of which the following is a specification.

This invention relates to a window, including sashes capable of being opened in a sliding or swinging manner.

An important object of the invention is the provision of a casement sash for window openings, so mounted as to be capable of swinging to an open position, in such manner that the sash, when opened, will be substantially parallel with the plane defined by the window opening and positioned substantially parallel to a wall.

20 A further object of the invention is the provision of a window of the above described class, which can be selectively used as the English upper and lower double hung sliding sash type, the swinging 25 Italian-French casement sash type, or a combination arrangement of the double hung and casement sash types.

Other objects and advantages will be apparent during the course of the following 30 detailed description.

In the accompanying drawings, forming a part of this specification, and in which similar reference characters designate corresponding parts throughout the several 35 views,

Figure 1 is a front elevation of the improved window showing the same in closed position.

Figure 2 is a front elevation of the improved window showing the same in open position.

Figure 3 is an enlarged perspective view of a latch member used in connection with the improved window.

45 Figure 4 is an enlarged fragmentary cross sectional view showing details of the window construction.

Figure 5 is an enlarged fragmentary cross sectional view showing the window in 50 open position when the sashes are used as in the casement type.

Figure 6 is a vertical cross sectional view taken on the line 6—6 of Figure 4.

In the drawings, wherein for the purpose of illustration is shown a preferred 55 embodiment of the invention, the letter A

designates the wall of a building having an opening therein for the window casing B. Upper and lower sash members C and D respectively are provided as closure members in the window casing B. Latch means E is provided in connection with each of the sash members C and D.

Reference herein to the use of the English type of window substantially means the upper and lower hung sliding sash construction; and to the Italian-French type of window, substantially means the swinging casement sash construction.

The window casing B simulates somewhat the ordinary window casing for the double hung type of English window, and includes the upper and lower rails 10 and 11 and the side members 12 and 13, said rails and members comprising the inside 70 house trim of the casing B. The ordinary stop beads 14 and 15 are positioned upon the right and left of the casing B. Sash weight boxes 16 are provided as in the ordinary arrangement, each of said boxes 80 including pulley stiles 18. Reinforcing stiles 20 are provided upon the right and left vertical edges of the window casing B, the same being of relatively greater width than the ordinary window member 85 used in its place, said members 20 providing outside closures for the sash weight boxes 16, and extending inwardly of the opening defined by the window casing B, past the stop beads 14 and 15, for a considerable 90 distance. The external surfaces of these reinforcing stiles are adapted for receiving sheathing, as well as for receiving the bracing strips 21 adjacent their inner ends 22.

The upper and lower sash members C and D are adapted for use in much the same manner as the double hung type of sliding sash, the upper member C being the outwardly disposed sash as in the ordinary arrangement, and separated from the inner 100 or lower sash D, by the vertical parting strips 25, which are arranged upon both of the right and left pulley stiles 18.

The upper sash members C preferably comprises right and left leaf sections 28 and 29 of exactly similar formation, in view of which fact a description of only one leaf 28 will be given. Similarly, the lower sash member D is divided into two similarly shaped leaf sections 30 and 31.

110 The leaf sections 30 and 31 are of like formation, for which purpose a description

of a single leaf 30 will be sufficient. The leaf 30 includes the pane supporting frame 35, which is hingedly mounted at 36 on a strip 37, to swing on a vertical pivot. The strip 37 being in turn hingedly mounted as at 38, to swing on a vertical pivot. The strip or member 39 to which the strip 37 is pivoted, is provided upon one face thereof with a vertical groove 40, adapted for receiving the outwardly projecting guide rail 41 embedded in the stop bead 14 and facing the parting strip 25. The strip 39 thus supports the strip 37 and the supporting frame 35 in hinged manner, and can be slid vertically in the window opening defined by the casing B. The strip 39 is provided with the ordinary sash cord 41^a, which inclines over the pulley 42 mounted in the stile 18, as is the case in ordinary arrangement, the sash weight 43 being supported upon the free end of the cord 41^a and within the sash weight box 16, as is the case in ordinary window construction.

Thus, it can be seen that either of the leaves 30 or 31 of the lower sash member D can be utilized as either a sliding sash or an inwardly swinging casement sash. When used as a casement sash, the strip 37 is swung inwardly upon its hinges 38 from the supporting strip 39, the frame 35 likewise being swung upon its hinges 36 inwardly from the intermediate strip 37. By this arrangement, it can be seen from an observation of Figure 5 of the drawings, that this hinged connection upon the leaf 30 will permit the pane supporting frame 35 to be swung clear of the stop bead 14 and just clear of the window casing B, in order to be positioned substantially parallel, when in an open position, with respect to the plane defined by the opening in the window casing B; in this position, lying parallel to the wall in which the window is positioned.

The leaf 28 immediately above the leaf 30 and which cooperates therewith, is altogether similar in construction to the leaf 30 above described. The same may comprise the pane supporting frame 50 hingedly connected by elements 52 to a corner edge of an intermediate supporting strip 53, said supporting strip 53 being connected by elements 54 to a corner edge of the sliding stile 55. The sliding stile 55 is provided with a vertical groove 56, adapted for receiving a projecting end of the guide rail 57 projecting from, and embedded in a side of a reinforcing piece 20. The sliding stile 55 is provided for exactly the same use as the sliding piece 39, and is provided with a sash cord 58 engaging over a pulley structure 59, a weight 60 being supported from the free end of the sash cord 58 and in the box 16 to facilitate sliding movement of the leaf section 28, as is the case in ordinary window construction.

The sliding stile 55 is of greater width than the sliding stile 39, projecting forwardly thereof into the opening of the window casing B, and in such manner that the intermediate supporting strip 53 when swung open upon its hinge will clear the intermediate supporting strip 37 of the leaf 30 of the lower sash member D. This intermediate supporting strip 53 is likewise of greater width than the supporting strip 37; and arranged in such manner, that when the pane supporting frame 50 of the leaf section 28 is swung in full open position upon its hinged members 52, the same will clear the pane supporting frame 35 of the leaf section 30 and ride parallel therewith and parallel with the plane defined by the opening in the window casing B. This arrangement is illustrated in complete manner in Figure 5 of the drawings, and shows the simple and compact arrangement with which the leaf sections 28 and 30 may be swung into full open position in cooperative manner.

The latch means E includes the cylindrical bolts 65 adapted for sliding in suitable recesses 66, which are provided in various places in the sash structures C and D, to be subsequently set forth, and adapted for sliding therein; a metal sleeve 67 being provided immediately adjacent the forward portion of a recess 66 and from which a projecting end 68 of the bolt 65 may extend for locking purposes. A notch 69 is provided adjacent the inner edge of the bolt member 65, to facilitate the manipulation by an operator to open the same.

When utilizing the improved window construction as the double hung English type, the meeting stiles 70 of sections 28 and 29 are locked together by a latch mechanism E, preferably just below the top rail 10 of the window casing B. Similarly, the leaf sections 30 and 31 of the bottom sash member D are locked together by the latch mechanisms E, which are placed adjacent the meeting stiles 71 of said leaf sections. In order to provide a very stable structure of each of the sash members C and D, latch mechanisms E are likewise provided supported from the pane carrying frames 35 and 50 and are adapted for having the bolt members 55 thereof shoved in suitable apertures transversely positioned through the hinged supporting strips 37 and 39 of the leaf sections 30 and 31. The bolts 65 supported from the leaf sections 28 and 29 engage through the supporting strips 53 and 55 substantially as illustrated in dotted lines in Figure 1 of the drawings. When the various latch structures E are arranged in their locked position, as above described for use of the upper sash members C and D as the double hung type of window, the sash members C and D can be reciprocated up and down in sliding manner much the

same as an ordinary window, the sash cords and sash weight facilitating such sliding movement.

When desiring to use the entire area of the window casing B, the various latch members E can be unlocked and the leaves 28, 29, 30 and 31 utilized in much the same manner as the Italian-French casement sashes. The leaf sections 30 and 31 are of course, adapted for the primary inward swinging, and the leaf sections 28 and 29 of the upper sash member C may be swung into parallel position over said leaf sections 30 and 31 in the manner above described.

Attention is directed to the fact that with the improved type of window construction only standard hinge and sash weight parts are provided, thus providing an economical structure capable of co-action either as the sliding frame or vertically pivoted sash type of window. Probably the greatest convenience served by the improved window type is the adaptation of the Italian-French casement window to sliding use, whereby the various leaves of the sash members may be swung inwardly out of the road and into parallel alignment with the wall supporting the window casing B. The various supporting strips for the pane supporting frames of the leaves 28 to 31 inclusive are hidden from view exteriorly of the building construction upon which the window frame is mounted, due to the reinforcing members 20 which overlie said supporting strips.

It is preferred, that all of the supporting strips of the leaf sections, as well as the leaf rails 70 and 71 of the sash members C and D be provided with tongue and groove joints, to provide a weather-proof window construction. The various leaves can be slid independently of each other and maintained in stable position in the window casing B, due to the guide rails 41 and 57, which cooperate with certain grooves in the supporting strips 39 and 55 in the manner above described.

The embodiment of the sliding and swinging window need not be restricted to the Italian-French type of casement window, since various important details of construction thereof are susceptible of embodiment in various window constructions. Rearrangement in the shape, size and arrangement of parts may of course be resorted to, without departing from the spirit of the invention or the scope of the claims.

I claim:

1. In a window, the combination of upper and lower sashes, means permitting sliding said sashes, and means permitting swinging 60 said sashes, said last mentioned means permitting open swinging of said sashes whereby to place said sashes in substantially parallel position with respect to the plane of the window opening and in overlapping relation to each other.

2. In a window, the combination with a casing defining a window opening, of upper and lower sash members, means mounting said sash members in double hung manner 70 for independent use as sliding sashes, each of said sashes including hinged means permitting swinging of said sash members in casement manner, said members adapted for swinging into full open position independent of each other to position the same in parallel relation with the plane defined by the window casing and in overlapping relation to each other.

3. A window construction comprising a 80 casing, a pair of stiles of unequal width vertically slidable at a side of said casing, intermediate stiles of unequal width hingedly connected to said sliding stiles, and sashes hingedly connected to said intermediate 85 stiles, said sashes being adapted for vertical movement in the window casing with the stiles, or to be laterally swung in horizontal manner to lie substantially in parallel overlapping relation.

PASQUALE DELLA MONICA.
